UNITED STATES PATENT OFFICE.

FREDERICK W. WILD, JR., OF BALTIMORE, MARYLAND, ASSIGNOR TO BURT MACHINE COMPANY, A CORPORATION OF DELAWARE.

LABELING-MACHINE.

No. 923,096.

Specification of Letters Patent.

Patented May 25, 1909.

Application filed January 2, 1908. Serial No. 408,966.

To all whom it may concern:

Be it known that I, FREDERICK W. WILD, Jr., of the city of Baltimore and the State of Maryland, have invented certain Improvements in Labeling-Machines, of which the following is a specification.

This invention relates principally to a peculiar construction of a labeling machine whereby certain parts of the same can be so adjusted one with another as to admit of the affixing of labels to cans of different diameters, as will hereinafter fully appear.

In the description of the said machine which follows, reference is made to the accompanying drawings forming a part hereof, and in which,—

Figure 1 is a partly sectional side view of the improved machine. Fig. 2 is an enlarged exterior side view of the entrance end of the machine, except that the front bar forming a part of the frame thereof is removed. Fig. 3 is a top view of the same, except that certain parts shown in Fig. 2 are removed, and the bar removed in Fig. 2 restored. Fig. 4 is a section of Fig. 3 taken on the dotted line $x-x$. Fig. 5 is an enlarged exterior side view of the central portion of the machine except that the front bar forming a part of the frame is removed as in Fig. 2. Fig. 6 is a top view of the said parts of the machine with the bar removed in Figs. 2 and 5 restored. Fig. 7 is an enlarged exterior side view of the delivery end of the machine with the bar before referred to removed. Fig. 8 is a top view of the same with the said bar restored. Fig. 9 is a view similar to Fig. 6, except that a modified construction of pasting devices is illustrated. Fig. 10 is an end view of Fig. 9 looking in the direction indicated by the arrow.

Referring now to Figs. 1 to 8 inclusive, of the drawings, the frame of the machine consists of the longitudinal and transverse bars respectively denoted by 1 and 2. The frame is supported by a stand which to facilitate the removal of the machine from place to place is provided with two truck wheels on a transverse axle b . One of these wheels is shown, and that is in Fig. 1 where it is represented by d . 3 and 4 are respectively, the entrance and the delivery runway for the cans, one of which cans is shown in Fig. 1 and marked X . 5, 5 are endless conveyer belts whereby the cans are carried longitudinally of the machine in the labeling opera-

tion, and the said belts are mounted on the pulleys 7 and 9, the latter being considerably smaller in diameter than the former, for a purpose hereinafter described. The shaft of the larger pulleys 7 which are situated at the entrance end of the machine, is supported in the standards 10, the lower ends of which rest and are adjustable in height in the sockets 12. This construction allows cans of different diameters to pass under and of their being carried forward by the belts; and when the said standards are adjusted in height they are fastened by means of the set screws e . 14 is the receptacle for cement which is liquefied by heat, and 15, 15 are wheels which are rotated in the cement receptacle by means of any suitable devices to apply cement to the bodies of cans as they are carried forward and over the said wheels by the conveyer belts 5. The cement receptacle is held in place by bolts f which depend from the forward transverse bar 2 of the frame, and pass through slots in extensions 16 of the said receptacle, as best shown in Figs. 2 and 3, whereby the receptacle is made adjustable in position. 17 is a fixed plate supported by the longitudinal bars 1 of the frame, having rails g which extend over the cement receptacle 14 and upon which the flanges of the heads of the cans roll.

By reference to Figs. 3 and 4, it will be seen that the rails g are placed exteriorly of the cement wheels, and that between the said wheels are situated two supplemental rails h which are fastened to the rear end of the cement receptacle, and elevated slightly above the rails g , as shown in Fig. 4. By this construction the cans immediately before reaching the cement wheels are lifted from the rails g by the supplemental rails h , and after passing from them, roll on to the plate 17. The supplemental rails h are set so as to be practically on a level with the top of the cement wheels, consequently the same amount of cement is invariably applied to the can bodies, which effect would not be the case should the cans at the time of the application thereto of the cement, be supported by the flanges of the heads, for the reason that the flanges of cans vary in thickness or projection beyond the bodies. 19 is the spring-held table upon which a stack of labels are placed, and by which the upper label is always held slightly below the surface of a label guide hereinafter described. 20 is the

label guide before referred to, consisting of fixed rails *i* which are supported from the longitudinal bars 1 of the frame by means of the rods *j*, and the longitudinally adjustable rails *k*. These adjustable rails are seated in depressions (see Fig. 5) in the fixed rails *i* with their forward ends covered by the projections *m* of the fixed rails, in order that at all times there is preserved a continuity of surface upon which the cans roll. 21 is a stretcher wire extending across the adjustable portion of the label guide to which its ends are fastened, from under which the rear end of the upper label is drawn by the rolling can.

Referring to Fig. 5, *y* is an edge on the fixed bars *i* of the label guide which in all cases is in vertical alinement with the forward edge of the stack of labels, and this edge must always bear a certain relation to the vertical center line of the cement wheels 15. For instance, in the affixing of labels to the largest cans, the distance between these two points will be practically the circumference of the can, in order that the portion of the can to which cement has been applied will roll over, and pick up the forward end of the top label of the stack, and the cement receptacle is therefore adjusted in position to effect that result. When cans of smaller diameter are to be labeled, the said distance must be a multiple of the circumference of the cans thus: If a can to be labeled has a circumference which is one-half that of the largest can, it would be practically impossible to decrease the distance between the said points one-half, consequently the said receptacle would be kept in its original position, and the cans would merely make two rotations before reaching the point *y*. But should the original distance not be a multiple of the circumference of the smaller cans, the cement receptacle would have to be moved longitudinally of the machine to such a distance that in a certain number of rotations of the can, the cemented portion of the can will come into contact with and pick up the forward end of the label. It must be borne in mind that the upper label of the stack of labels is flush with the top edge of the longitudinal bars 1, and by reference to Fig. 5 of the drawing, it will be seen that the edge *y* of the label guide is below the label, and from near that point, the guide rises to a height which is above the said rails, and this increased height is maintained until the can is about to come into contact with and press upon the pasting belt 24. The object of this construction is to make the can during the labeling operation, traverse a greater distance than the length of the label the end of which is drawn from under the wire 21, thus placing sufficient tension on the label to cause it to be wrapped tightly around the can. 22 is a

paste pot supported by one of the longitudinal bars 1 of the frame along which it is adapted to be slid, and the means for its attachment to the said bar is of such character as to admit of the adjustment of the paste pot with respect to the adjustable portion of the label guide and particularly to the wire 21. 24 is an endless pasting belt which is carried by a wheel 18 in the paste pot, and a sheave 25 which is tight on the shaft 27 (see Fig. 6) but which is moved longitudinally of the said shaft when the paste pot is adjusted, and thereby brought into alinement with the paste wheel.

By reference to Fig. 5 it will be seen that the lower lay of the pasting belt which applies paste to the label, enters the paste pot near its bottom, and in consequence, very thin paste cannot be used, as it would leak from the pot. 30, 30 are tension pulleys supported by inclined bars 31 adapted to slide in bosses *n* formed on the standards 33 which support the shaft 34 of the smaller pulleys 9 which together with the larger pulleys 7, before referred to, carry the conveyer belts 5. The object in making the pulleys 9 smaller in diameter than the pulleys 7, is to provide for the labeling of cans of various diameters, without vertical adjustment of the standards 33. The conveyer belts at the delivery end of the machine when slightly deflected in a downward direction by pressure thereon of the tension pulleys 30 have such height above the cushioned bed 35 as to exert the desired pressure on the labels of cans of the largest diameter being labeled. Owing to the inclined position of the bars 31, and their longitudinal adjustability, a forward movement of the said bars lowers the tension pulleys 30 and the lower lay of the conveyer belts upon which they bear, and thereby causes them to bear on the labels of cans of a smaller diameter. 37 is a roller arranged to bear with a yielding pressure on the lower lay of the conveyer belts at the point where the can is about to cross the pasting belt as it reaches the rear end of the label, and it is fastened to a rod 39 longitudinally adjustable within a block 40 placed loosely on the shaft 34 of the pulleys 9. 36 is a gravity roller which rests on the lower lay of the endless conveyer belts 5, at a point directly over the forward or entrance end of the label table 19. In the rapid passage of cans under the roller the same has imparted to it a vertical vibratory movement and practically strikes the belt over each can at the time that its cemented portion comes into contact with the forward end of the label, thus causing the label to adhere to the can more fully than if the can were subjected merely to the weight of the roller.

I am aware that it is not new to apply tension rollers to belts, but in my invention

the action of the roller is similar to the blow from a hammer in which the force exerted, is considerably greater than that due to the weight of the descending body.

The pasting belt is normally clear of the label, but is pressed down and brought into contact with it by the can. Depressions *o* in the adjustable rails *k* of the label guide receive the pasting belt when forced down by the can, at the place where the ends of the labels are lapped. In some cases it is desirable to use very thin paste and as such would leak from the aperture through which the lower lay of the pasting belt enters the paste pot, I employ the pasting devices shown in Figs. 9 and 10 to which reference should be made. In the said figures, the pasting belt 24 does not enter the paste pot 22 but receives its coating of paste from the circumference of the rotary disk 41 which is situated in the pot and receives its rotation from the said belt; and in order that the pressure of the disk on the belt will be uniform notwithstanding variations in the thickness of the belt, the paste pot is pivoted by means of bolts to lugs 42 between the brackets 43 which carry the shaft 45 of the pasting belt wheel 47, and is spring-held. The spring mechanism which I preferably use to yieldingly sustain the paste pot, consists of a spring 49 fastened to the pot, a rigid bar 50 depending from the base of standard 43, and a tension screw 51 in the bar, the point of which screw bears against the plate spring as shown in Fig. 10.

Supposing the various parts of the machine to be in the relative positions shown in Fig. 1, the machine being thereby adapted to affix labels to cans of the greatest diameter, and it is desired to prepare the machine to label cans of a smaller diameter, the following adjustments are made. The standards 10 are lowered in their sockets 12 the proper distance and secured. The adjustable rails *k* of the label guide are next moved to the left in Fig. 1 so as to bring the stretcher wire 21 to a place where it will press near to the rear end of the shorter label which must be used. The pasting devices as an entirety are then slid along the frame of the machine until the pasting belt is directly over the depressions *o* in the adjustable rails *k* of the label guide. The tension pulleys 30 are then adjusted so that the lower lay of the conveyer belts will bear properly on the cans to be labeled, and the roller 37 moved forward so as to press down the belt on the can immediately before the can reaches the pasting belt. The cement receptacle is now moved to a position wherein the distance between its cement wheels and the edge *y* of the fixed rails of the label guide will be a multiple of the circumference of the cans. The label table is then provided with a stack of labels of the required length which are

placed in proper position thereon, and the machine is set in motion, when the labeling operation is performed in the usual manner.

I claim as my invention:

1. In a labeling machine, devices to apply cement to a can upon its entrance to the machine, a label guide having a movable section which embodies a device to bear upon the rear end of the label to be applied to the can, and which is susceptible to adjustment with respect to the cement applying devices, and a paste-applying mechanism which is adjustable in position with respect to the movable section of the label guide, combined with a vertically adjustable conveyer belt, substantially as specified.

2. In a labeling machine, a label guide in two sections, viz: a fixed and a movable section, the latter resting in a depression in the former, and the former having a projection which extends over the end of the latter, whereby in the extension and contraction of the guide continuity of the upper surface of the guide is maintained, substantially as specified.

3. In a labeling machine, a horizontal label guide, a conveyer belt to roll cans longitudinally of the guide, combined with a tension pulley to bear on the lower lay of the belt, the said pulley being carried by a bar adapted to have a sliding movement within a fixed bearing which is in an inclined position with respect to the said label guide, substantially as specified.

4. In a labeling machine, a label guide upon which the cans are rolled in the labeling operation, and an endless conveyer belt to effect the rolling of the cans, combined with a gravity roller attached to the end of a bar, and a pivoted block through which the said bar is adapted to slide, substantially as specified.

5. In a labeling machine, an endless pasting belt, a paste pot pivoted to some stationary part of the machine, and a paste wheel situated in the paste pot, combined with spring mechanism whereby the paste pot is supported and its paste wheel held in contact with the pasting belt, substantially as specified.

6. In a labeling machine, the combination of a label guide upon which cans to be labeled are rolled, an endless conveyer belt situated over the label guide, and a pivoted tension roller which bears with a yielding pressure on the lower lay of the endless belt, the said roller being adjustable longitudinally of the belt, substantially as specified.

7. In a labeling machine, a cement receptacle, cement applying wheels situated within the cement receptacle, rails which extend across the cement receptacle, upon which the flanges of the heads of the cans roll, combined with upwardly curved supplemental rails which are placed between the other

4
rails with their central portion elevated above them, and approximately on a level with the upper edge of the cement wheels, whereby the bodies of the cans are brought 5 momentarily into contact with the cement wheels and prevented from rolling over an extended portion of their circumference, without reference to their vertical position before reaching the cement wheels, substantially as specified.

10 8. In a labeling machine, the combination

of a label guide upon which cans to be labeled are rolled, an endless conveyer belt situated over the label guide, a label table and a gravity roller which bears on the lower lay 15 of the endless belt at a point over the forward or entrance end of the label table, substantially as specified.
